UNITED STATES PATENT OFFICE.

LOUIS MARINSKY, OF NEW YORK, N. Y., ASSIGNOR TO ISRAEL F. GREENBAUM, OF BROOKLYN, NEW YORK.

MACHINE FOR AUTOMATICALLY ATTACHING CLOSING-CLIPS FOR FLEXIBLE TUBES.

1,378,596.

Specification of Letters Patent.

Patented May 17, 1921.

Application filed July 2, 1919. Serial No. 308,235.

To all whom it may concern:

Be it known that I, LOUIS MARINSKY, a citizen of Russia, and residing at New York, in the county of Bronx and State of New York, have invented certain new and useful Improvements in Machines for Automatically Attaching Closing-Clips for Flexible Tubes, of which the following is a specification, such as will enable those skilled in the art to which it appertains to make and use the same.

This invention relates to machines designed for use in the manufacture of flexible tubes used as containers for dental paste and creams, library paste and various other products, and the object of the invention is to provide a machine which is adapted to automatically apply the closing or sealing clips to the bottom or open ends of such tubes after the same has been filled with the desired contents; and with this and other objects in view the invention consists in a machine of the class and for the purpose specified which is simple in construction and efficient in use and which will produce a great saving in the manufacture of articles or containers of the class specified and which will also produce a better and more positively sealed article or container.

The invention is fully disclosed in the following specification, of which the accompanying drawings form a part, in which the separate parts of my improvement are designated by suitable reference characters in each of the views, and in which:—

Figure 1 is a side view of my improved machine with parts of the construction broken away and in section;

Fig. 2 a partial section on the line 2—2 of Fig. 1;

Fig. 3 a longitudinal and broken sectional view of the machine, the sections being on the line 3—3 of Fig. 4 of the drawing;

Fig. 3^a a longitudinal and broken sectional view of the machine, the section being on the line 3^a—3^a of Fig. 4 of the drawing;

Fig. 4 a plan view of the machine with parts of the construction broken away;

Fig. 5 a partial section on the line 5—5 of Fig. 3 with the parts in a different position;

Fig. 5^a a view similar to Fig. 3 but showing only a part of the construction on an enlarged scale, and showing the same in differ-

ent positions and indicating the operation of the machine;

Fig. 6 a view similar to Fig. 5 but showing the parts in a different position;

Fig. 6^a a view similar to Fig. 5^a showing other details of construction with the parts in a different position, and showing another step in the operation of the machine;

Fig. 7 a partial section on the line 7—7 of Fig. 1 and on an enlarged scale; 65

Fig. 8 a partial section on the line 8—8 of Fig. 6^a;

Fig. 9 a partial section on the line 9—9 of Fig. 6^a; and,

Fig. 10 a detail view of parts of the construction shown in Fig. 3^a detached, and indicating the method of connecting the same. 70

In the drawings I have shown at 11 a base frame which is hollow and oblong in form, the end portion 12 of which is of approximately cylindrical form and a shaft 13 is mounted longitudinally of the base frame 11 in bearings 14. A beveled gear 15 is secured to said shaft within the cylindrical portion 12 of the frame as shown in Fig. 1, and adapted to operate in connection with another beveled gear 16 secured to the lower end of a vertical shaft 17. 75

Mounted on the shaft 17 is a vertical sleeve 18 which is permanently mounted in the top central portion of the cylindrical portion 12 of the frame as shown at 19, and the upper end portion of the sleeve is provided with elongated gear or sprocket teeth on its outer face as shown at 20 in Fig. 7 of 90 the drawing. Rotatably mounted on the central portion of the sleeve 18 is a conical workpiece supporting member or table 21, comprising a central sleeve portion 22, a top portion 23, a downwardly and flaring rim portion 24 and adjacent to the bottom of the sleeve portion 22 is an annular flange 25. 95

A supplemental or disk-shaped frame 26 is mounted on the upper end portion of the sleeve 18 and provided with a raised keeper 27 and with a raised block 28, as shown in Fig. 9 of the drawing, said block being provided with an elongated rectangular aperture 29 and at the top of which is a beveled track or slide-way 30. 100

A slide or jaw member 31 is movably mounted in the aperture 29 and a carriage 32 is slidably mounted in the beveled track or slide-way 30 as clearly shown in Figs. 110

5^a, 6^a and 9 of the drawing. The carriage 32 is provided with two upstanding ears 33 in which is movably mounted a longitudinal rod 34, one end of which is secured to the 5 keeper 27 as shown at 35, and a spiral spring 36 is mounted between the keeper 27 and one of the ears 33 and two adjusting and lock nuts 37 are mounted on the rod 34 outwardly of the other of said ears 10 33, the end of said rod being forked to receive a link 38, one end of which is pivoted within said forked portion of rod 34 as shown at 39 and the other end of said link is pivoted to an upwardly directed fork 40 15 on a lever 41 pivotally mounted in the forked end 42 of the carriage 31 as clearly shown in Figs. 3, 5^a, 6^a and 8 of the drawing. The free end of the lever 41 is enlarged to form a hammer face 43 the function of which is hereinafter set out.

The inner end portion of the carriage 32 is provided in the bottom face thereof with an anti-friction roller 44, and a similar anti-friction roller 45 is mounted in a transverse 25 aperture 46 in the inner face of the slide or jaw member 31, and a cam member 47 provided with independent cam faces 48 and 49 is secured to the upper end portion of the shaft 17 in such position that the 30 cam face 48 will operate in connection with the roller 44, and the cam face 49 in connection with the roller 45.

A supplemental jaw member 50 is mounted in the slide or jaw member 31 and provided with inwardly directed rods 51 on which are mounted springs 52 which operate in apertures 53 in the jaw member 31, and the jaw member 50 co-operates with the slide or jaw member 31 hereinafter described. A 35 vertical pin 54 is secured centrally of the member 31 and passes downwardly through an aperture 55 in the supplemental or disk-shaped frame 26, and one end of a spiral spring 56 is secured to said pin and to a 40 screw 57 secured to the frame 26 as clearly shown in Fig. 6^a of the drawing, and this spring serves to move the slide or jaw member 31 in one direction.

The workpiece supporting member 21 is 45 provided on its top face with two pawls 58 which operate in connection with the ratchet teeth 20 on the sleeve 18 as clearly shown in Fig. 7, and these pawls are normally held in engagement with said teeth by springs 59. Mounted on the face of the conical or 50 flaring portion 24 of the member 21 adjacent to the top face thereof are a plurality of pairs of outwardly directed pins 60 below each pair of which an L-shaped plate 61 is adjustably secured as shown at 62, to the face of the conical or flaring portion 24, the protruding portion of said L-shaped plate being provided with an aperture 63, and these plates and the separate pairs of 65 pins 60 form supports and guides for flexi-

ble tubes 64, one of which is indicated in dotted lines in Fig. 3, and the upper end portion of another of which is shown in full lines in Figs. 5^a and 6^a. The screw cap ends 65 of the tubes 64 are adapted to enter 70 the apertures 63 in the plates 61, and the larger or flattened ends of said tubes are adapted to be held between the separate pairs of pins 60 with the folded ends 66 of said tubes resting upon the periphery of the 75 supplemental or disk-shaped frame 26.

The member 21 is given an intermittent rotary movement on the sleeve 18 and controlled by the pawls 58, and an intermittent vertical movement by a plurality of downwardly directed pins 67 secured to the annular flange 25, four of which are preferably employed. A cam member 68 is provided with a plurality of raised portions 69 and a corresponding number of recessed 80 portions 70 in connection with which the pins 67 operate. The member 21 is held in its raised position by the pins 67 resting upon the flat faces 71 on the top of the raised portions 69, and when said pins are 85 in the last named position the member 21 will assume a position similar to that indicated in Fig. 6^a of the drawing. The work-piece supporting member 21 is given its intermittent rotary movement by the raised 90 portions 69 of the cam member 68 striking or bearing on the pins 67 in the oscillation of said cam member, as hereinafter set out.

The cam member 68 is provided on one side thereof with an extension 72 in which is secured a downwardly directed pin 73 which passes through an elongated aperture 74 in the top of the base frame 11 and a crank arm 75 is pivoted to the frame 11, as shown at 76, and provided at its free end with an upwardly directed arc-shaped portion 77 in connection with which the pin 73 operates. The crank 75 is given an oscillatory movement by a downwardly directed pin 78 operating in an aperture 79 in the 100 crank arm 75, and this oscillatory movement of the arm 75 will correspondingly move the pin 73 to give the cam member 68 a 105 rotary, oscillatory movement.

At one side of the base frame 11 is an 110 upwardly directed clip feeding device 80 which is adapted to supply a plurality of elongated V-shaped clips 81 to the supplemental frame 26 of the machine.

The device 80 is composed of two approximately similar side parts 82 which are joined centrally, said parts being provided with a flanged base 83 through which screws or bolts 84 are passed for securing the device to the frame 11, and centrally of the flanged base 83 are upstanding box members 85 which terminate at 86, and which are provided with web constructions 87 which join the box members 85 with a hopper-shaped top portion 88 also composed of separate 115 120 125 130

similar side parts. The opposite sides of the hopper-shaped member 88 are closed by plates 89 set within the same and the sides of the device 80, as a whole are closed by 5 vertical strips 90, these connections being made by welding, bracing, riveting or otherwise. The front and back walls of the device 80 are provided with a plurality of vertical slots 91, 92 and 93 which extend through 10 the separate parts of said device, as clearly shown in Figs. 1 and 3^a. Movable mounted between the separate parts 82 of the device 80 where they abut is a vertical blade 94, the top of which is beveled as shown at 15 95 and inclined downwardly and inwardly, and a plurality of transverse blades 96 are secured to the blade 94 as shown in Fig. 3, and are adapted to operate in the slots 91, 92 and 93 in the vertical movement of the blade 94. 20 The blade 94 is provided at its lower end with a link lever 97 which is pivotally connected thereto as shown at 98, and the lower end of said lever is provided with an elongated aperture 99 through which is passed 25 a pin 100 secured to the free end of a crank 101 mounted on the shaft 13. This construction serves to move the blade 94 vertically in the device 80 in such manner as to pick up a number of the clips 81 as shown 30 in Fig. 3 of the drawing and to permit of their discharge through an aperture 102 in one of the side walls 80 onto an inclined runway 103 as shown in Figs. 1 and 3 of the drawing. The runway 103 is secured to the 35 device 80 and extends toward the frame 26 and provided with a rectangular head 104 secured to said frame as shown at 105.

It will be noted that the clip feeding device 80 is secured to the base frame 11 in 40 such position that the runway 103 and said device extends toward the frame 26 at a tangent thereto or at right angles to the movement of the carriage 32 and the slide or jaw member 31, as clearly illustrated in 45 Fig. 4 of the drawing. It will be understood that a number of clip devices are placed within the hopper 88 of the clip feeding device 80 and the vertical movement of the blades 94 and 96 therein will cause the 50 blade 94 to pick up a number of said clips as illustrated in Fig. 3, the blades 96 serving to break up or scuffle the clips in the device 80 to facilitate this operation.

The operation of my improved machine 55 will be readily understood on a consideration of the foregoing description when taken in connection with the accompanying drawing and the following statement. It will be understood that the supplemental or disk-shaped frame 26 and the clip feeding device 80 are stationary while the workpiece supporting member 21 has an intermittent rotary movement in the direction of the arrow *x* Fig. 4, and an intermittent vertical movement and the carriage 32 and the

slide or jaw member 31 have intermittent forward and backward movements on the frame 26. As the workpiece supporting member 21 rotates the tubes 64 are placed in position as is illustrated in dotted lines 70 in Fig. 3, prior to their passage into alignment with the slide or jaw member 31, and in this operation a sealed tube may be removed from the holder and an unsealed tube replaced therein by one operator, the holder 75 or holders consists of the pairs of pins 60 and the L-shaped plates 61.

When a tube 64 is in alignment with the jaw member 31 as is illustrated in Fig. 3 of the drawing, the rotary movement of the 80 workpiece supporting member 21 stops and at this time the cam face 48 on the cam member 47 operates in connection with the roller 44 to move the carriage 32 inwardly, the completion of which operation is indicated 85 in full lines in Fig. 5^a of the drawing. It will be noted that the folded top portion 66 of the tube is struck by, or pressed by the hammer face 43 of the lever 41 to straighten 90 said folded end, after which the carriage 32 95 again moves into the position shown in dotted lines in Fig. 5^a and in full lines in Fig. 3, and the workpiece supporting member 21 is moved upwardly. Prior to, or at the time of this last operation, however, the 100 slide or jaw member 31 is moved outwardly by a raised portion 49^a on the cam member 47, which operates in connection with the roller 45 to move the jaw member 31 of the supplemental spring actuated jaw 50 thereof 105 outwardly a slight extent to grasp a clip in the manner shown in Fig. 5^a of the drawing and to extend one side of said clip outwardly. It will be understood that the clip referred to is supported on the upwardly directed extension 104^a on the top of the rectangular head 104 of the runway 103.

In the next operation of the machine, the workpiece supporting member 21 moves upwardly to bring the folded end 66 of the tube beneath the side extension of the clip 81, and this upward movement continues until the tube 64 with the clip thereon is in the position shown in Fig. 6^a at which time the cam face 49 operates in connection with the roller 45 to move the jaw member 31 outwardly to compress said clip onto the folded end 66 of the tube 64, this result being accomplished by the jaw member 31, or the outer face thereof, and a downwardly directed portion 110 106 on the carriage 32, which forms a stationary jaw member. In this last operation it will also be noted that the supplemental jaw member 50 is held against outward movement by the raised portion 104^a, as clearly 115 shown in Fig. 6^a of the drawing, and when the jaw member 31 again moves inwardly by the spring 56, the tube 64 will be released and at this time the workpiece supporting member 21 moves downwardly and is again ro- 120 125 130

tated one step, or one-eighth of a revolution to bring another tube placed upon said member 21 into alinement with the jaw member 31 and the various parts that operate in connection therewith.

At each revolution of the shaft 13, the blades 94 and 96 are moved upwardly and downwardly in the clip feeding device 80 and the blade 94 being held stationary to a slight extent at the limit of its upward movement to permit of the sliding of the clips 81 onto the runway 103, this result being accomplished by the elongated slot 99 through which the pin 100 passes.

The oscillatory movement of the cam member 68 is produced by the pin 78 rotated in the elongated slot 79 by the crank 75, and the engagement of the pin 73 of said member with the upwardly directed arc-shaped portion 77 and in said oscillatory movement of the cam member 68, the pins 67 carried by the workpiece supporting member move upwardly and downwardly over the raised portions 69 of said cam member.

It will be readily understood that machine effects a great saving of time and labor and produces a more perfectly sealed tube or other article of the class specified, and although I have shown certain details of construction for carrying my invention into effect, it will be apparent that I am not necessarily limited to these details, and various changes therein and modifications thereof may be made, within the scope of the appended claims, without departing from the spirit of my invention or sacrificing its advantages. It will be understood that the shaft 13 which extends through one side of the base as shown in Fig. 1 may be rotated or driven in any desired manner by a pulley and belt construction, or gear construction from a suitable motor, but as this forms no part of my invention the same has not been shown or described.

Having fully described my invention, what I claim as new and desire to secure by Letters Patent, is:—

1. In a machine of the class described, a workpiece supporting member, means for supporting a plurality of tubes on said member, means for giving said member a combined intermittent rotary and vertical movement, means for straightening one end of said tubes, means for placing V-shaped sealing clips on said end portion of said tubes in the vertical movement of said member, and means for compressing said clips onto said end portions of the tubes.

2. In a machine of the class described, a workpiece supporting member, means for supporting a plurality of tubes on said member, means for giving said member a combined intermittent rotary and vertical movement, means for automatically feeding sealing clips to the machine, means for straight-

ening one end portion of said tubes, means for placing said clips on said end portion of the tubes in the upward movement of said workpiece supporting member, and means for compressing said clips on said end portion of said tubes.

3. In a machine of the class described, a workpiece supporting member, means for supporting a plurality of tubes on said member, means for giving said member a combined intermittent rotary and vertical movement, a stationary and movable jaw member arranged above said workpiece supporting member, means for feeding sealing clips to the machine and for supporting a clip between said jaw members and one of the tube supporting means on said member, and means for straightening one end portion of a tube supported below said jaw members, whereby in the upward movement of said workpiece supporting member a sealing clip will be passed onto said straightened end of the tube and placed thereon by said jaw members.

4. In a machine of the class described, a member adapted to support a plurality of tubes, means for giving said member an intermittent rotary movement, means for giving said member an intermittent movement in a line parallel to the axis thereof, means adapted to operate in connection with one end portion of the tubes supported by said member for straightening one end of said tubes, means for placing clips upon the straightened ends of the tubes in the last named movement of said member, and means for compressing said clips onto said tubes.

5. In a machine of the class described, a base, a member rotatably mounted on said base and adapted to support a plurality of tubes, a disk-shaped frame at the top of said member, means for giving said member a rotary oscillatory movement, means for moving said member toward and from said disk-shaped frame, means for feeding sealing clips to said disk-shaped frame, and movable jaw members mounted on said frame and adapted to compress said clips onto one end portion of the tubes supported on said member.

6. In a machine of the class described, a base, a member rotatably mounted on said base and adapted to support a plurality of tubes, a disk-shaped frame at the top of said member, means for giving said member a rotary oscillatory movement, means for moving said member toward and from said disk-shaped frame, means for feeding sealing clips to said disk-shaped frame, movable jaw members mounted on said frame and adapted to compress said clips onto one end portion of the tubes supported on said member, and a hammer device carried by said frame and adapted to straighten the ends

of said tubes to which the clips are attached prior to securing the clips thereon.

7. In a machine of the class described, a base, a vertical shaft mounted in the base, 5 a sleeve mounted on said shaft, a work-piece supporting member rotatably mounted on said sleeve, means on the lower end portion of said shaft and within the base for rotating said shaft, means for giving said 10 workpiece supporting member an intermittent rotary movement, a frame mounted on the upper end portion of said sleeve, a hammer device movably mounted on said frame and operated in one direction by a spring, 15 jaw members movably mounted on said frame, tensional means for operating said jaw members in one direction, and means mounted on the upper end portion of said shaft and adapted to operate said hammer 20 device and said jaw members.

8. In a machine of the class described, a base, a vertical shaft mounted in the base, a sleeve mounted on said shaft, a work-piece supporting member rotatably mounted 25 on said sleeve, means on the lower end portion of said shaft and within the base for rotating said shaft, means for giving said workpiece supporting member an intermittent rotary movement, a frame mounted on 30 the upper end portion of said sleeve, a hammer device movably mounted on said frame and operated in one direction by a spring, jaw members movably mounted on said frame, tensional means for operating said 35 jaw members in one direction, means mounted on the upper end portion of said shaft and adapted to operate said hammer device and said jaw members, a sealing clip feeding device mounted on the base and adapted 40 to feed clips to said frame, means for detachably supporting a plurality of tubes on said workpiece supporting member, and means whereby in the upward movement of said member one of said clips will be placed 45 on one end portion of one of the tubes supported by said member.

9. In a machine of the class described, a base, a longitudinal drive shaft mounted therein, a vertical shaft geared in connection 50 with said longitudinal shaft, a sleeve mounted on said last named shaft, a disk-shaped frame secured to the upper end portion of said sleeve, a workpiece supporting member rotatably mounted on said sleeve 55 and movable toward and from said disk-shaped frame, a sealing clip feeding device supported on the base, a plurality of blades movably mounted in said feeding device, means in operative connection with said 60 longitudinal shaft for operating said blades, means for feeding clips from said clip feeding device to the periphery of said disk-shaped frame, and means for detachably supporting a plurality of tubes on said 65 workpiece supporting member with one end

portion of said tubes resting upon the periphery of said frame.

10. In a machine of the class described, a base, a longitudinal drive shaft mounted therein, a vertical shaft geared in connection with said longitudinal shaft, a sleeve mounted on said last named shaft, a disk-shaped frame secured to the upper end portion of said sleeve, a workpiece supporting member rotatably mounted on said sleeve 70 and movable toward and from said disk-shaped frame, a sealing clip feeding device supported on the base, a plurality of blades movably mounted in said feeding device, means in operative connection with said longitudinal shaft for operating said plates, means for feeding clips from said clip feeding device to the periphery of said disk-shaped frame, means for detachably supporting a plurality of tubes on said work- 75 piece supporting member with one end portion of said tubes resting upon the periphery of said frame, means for giving said workpiece supporting member an intermittent rotary movement to bring the successive tubes in position to receive a sealing clip positioned on said disk-shaped frame, and means for giving said workpiece supporting member an intermittent movement toward and from said frame to place a clip 80 on the end of the one of the tubes supported by said member. 90

11. In a machine of the class described, a base, a longitudinal drive shaft mounted therein, a vertical shaft geared in connection 100 with said longitudinal shaft, a sleeve mounted on said last named shaft, a disk-shaped frame secured to the upper end portion of said sleeve, a workpiece supporting member rotatably mounted on said sleeve and 105 movable toward and from said disk-shaped frame, a sealing clip feeding device supported on the base, a plurality of blades movably mounted in said feeding device, means in operative connection with said longitudinal shaft for operating said plates, means for feeding clips from said clip feeding device to the periphery of said disk-shaped frame, means for detachably supporting a plurality of tubes on said work- 110 piece supporting member with one end portion of said tubes resting upon the periphery of said frame, means for giving said workpiece supporting member an intermittent rotary movement to bring the successive tubes in position to receive a sealing clip positioned on said disk-shaped frame, means for giving said workpiece supporting member an intermittent movement toward and from said frame to place a clip 115 on the end of the one of the tubes supported by said member. 120
12. In a machine of the class described, a base, a longitudinal drive shaft mounted therein, a vertical shaft geared in connection with said longitudinal shaft, a sleeve mounted on said last named shaft, a disk-shaped frame secured to the upper end portion of said sleeve, a workpiece supporting member rotatably mounted on said sleeve and 125 movable toward and from said disk-shaped frame, a sealing clip feeding device supported on the base, a plurality of blades movably mounted in said feeding device, means in operative connection with said longitudinal shaft for operating said plates, means for feeding clips from said clip feeding device to the periphery of said disk-shaped frame, means for giving said workpiece supporting member an intermittent movement toward and from said frame to place a clip on the end 130 of one of the tubes supported by said member, a carriage movably mounted on said frame, a jaw member movably mounted on said frame, rollers carried by said carriage and jaw member, and a cam member mount-

movement, a hammer device operated by said carriage and adapted to straighten the end of a tube resting upon the periphery of said disk-shaped frame prior to placing 5 the sealing clip thereon, tensional means for moving said carriage and hammer device in one direction, tensional means for moving said jaw member in one direction, a supplemental tensionally controlled jaw member 10 carried by said first named jaw member, the upper end portion of said sleeve being provided with a plurality of ratchet teeth and spring actuated pawls mounted on said

workpiece supporting member and operating in connection with said ratchet teeth to prevent the rotary movement of said member on 15 said sleeve in one direction.

In testimony that I claim the foregoing as my invention I have signed my name in presence of the subscribing witnesses this 20 30th day of June 1919.

LOUIS MARINSKY.
